TIME INDICATOR

Leonard C. Butts, Spokane, Wash.

Application October 26, 1931. Serial No. 571,126

5 Claims. (Cl. 58—26)

The object of this invention is to provide a novel type of distance time indicator whereby the time of day or night can be seen at a long distance.

5 A feature of the invention consists in a clock dial and minute and hour hands of large or gigantic proportions adapted to be mounted in an upright position at a high elevation or against the side of a hill or mountain, in combination with mechanism adapted to be set in operation by a master clock for causing advancement of the hands to indicate correct time of day or night.

10 Thus the main portion of the structure of this invention is not in itself a clock or time keeping device but rather a structure that is controlled and actuated by a time keeping device.

15 A feature of the invention consists, in the combination claimed, of minute and hour hands operatively connected to control their relative advancing movement in clock-like or time indicating relation by means which preferably consists in a dial train of gears, so that movement of one of said hands will cause a corresponding relative movement of the other of said hands.

20 25 A further feature consists in means located near the outer end of one of said hands for causing advancing movement of both hands.

30 35 A further feature consists of means carried by and rotating with the inner or central portion of the structure and extending outwardly along one of the hands for imparting drive to the outwardly disposed means for advancing such hand.

40 The invention also comprises a combined locking and advancing ring abreast of which the outer end of one hand moves, in combination with means engaging said ring for periodically advancing said hand, together with means for periodically locking said hand in its advanced position and then releasing the hand for further advancing movement.

45 The invention has many other features and objects which will be more fully described in connection with the accompanying drawings and which will be more fully described and pointed out by the appended claims.

In the drawings:—

Fig. 1 is a face view of the device of my invention with the latter in an upright position.

50 Fig. 2 is a sectional view on line 2—2 of Fig. 1, with the parts shown on an enlarged scale.

Fig. 3 is a sectional view on line 3—3 of Fig. 2.

Fig. 4 is a sectional view on line 4—4 of Fig. 1.

Fig. 5 is a sectional view on line 5—5 of Fig. 1.

55 Fig. 6 is a diagrammatic view of the electric wiring employed in the device of my invention.

Like characters of reference designate similar parts throughout the different figures of the drawings.

The structure of my invention includes a clock dial formed of numerals 1 to 12, as indicated at 60 1, which numerals may be suitably mounted on a frame work 2, adapted to be supported in any desired manner, dependent upon whether the structure is mounted on top of a building or on the side of a hill. Thus the particular manner 65 in which the structure is mounted is not material to my invention and is within the range of mechanical skill, in view of the present disclosure.

Movable abreast of the dial are minute and 70 hour hands 3 and 4, respectively, the former being disposed outermost or forwardly of the latter. A main arbor 5, preferably tubular, is journaled in bearings 6 and 7, mounted in any desired manner and disposed horizontally, in the 75 present construction, whereby said arbor will rotate about a horizontal axis. A sleeve 8, rigidly mounted on said arbor, has a flange head 9, to which a centrally enlarged portion 10, of hand 3, is rigidly mounted, as by means of bolts 11. 80 Said minute hand 3, has a stem portion 12, extending to the right of arbor 5, viewing Fig. 1, on which an adjustable counter-weight 13, is mounted. This counter-weight not only balances 85 the larger end of said hand 3, but also the mechanism carried thereby, as will later appear.

85 Loosely mounted on said arbor 5, between collars 14 and 15 which are fixed to said arbor, is a dial sleeve 16 having a head flange 17, to which the inner end of the hour hand 4, is suitably 90 bolted as indicated at 18. Fixed on sleeve 16 is one gear member of a dial train indicated at 19. A counter-shaft 20, mounted in bearings 21 and 22, has fixed thereto a dial pinion 23, which meshes with dial gear 19, and also a dial gear 24, 95 is mounted on shaft 20 and meshes with dial pinion 25, which latter is fixed on arbor 5. It will thus be seen that rotary motion is transmitted from pinion 25 to gear 24, and from the latter to pinion 23 back to gear 19, whereby the hour hand 4 will move or advance from one dial numeral 1, to another, every time the minute hand 3 advances a complete revolution abreast of the dial. It will thereby be seen that this dial train will control the relative advancing movement 100 of the hands 3 and 4, and that any advance or stopping by one hand will cause a relative advance or stoppage of the other.

105 Mounted on what may be termed, broadly, the inner or central portion of the minute hand 3, 110

but which is specifically disposed on the arbor 5, is a hub 26, provided with a shelf 27, the purpose of which will later appear.

A sleeve 23, which may be of insulating material, is secured to arbor 5, and carries contact rings 29 to 32, with which brushes 33 to 36, respectively, contact, the purpose of which will later appear, and all of which is clearly shown in Fig. 4.

10 Reference will next be made to Figs. 1, 2 and 3, for description of a feature of the invention whereby one of the hands is advanced, periodically and periodically locked and then released for further advancement.

15 A combined locking and propulsive ring is indicated at 37 and is rigidly mounted in the relation to hand 3, as shown in Fig. 1. The outer periphery is provided with rack teeth 38, and the inner periphery is provided with a series of spaced 20 locking notches 39, sixty in number and located in the relation shown with respect to the time ordinals 1. A platform 40, is pendently supported by brackets 41 and 42 from the lower outer face of minute hand 3, as shown in Fig. 3. Retaining discs 43 and 44 are mounted on spindles 25 45 and 46 that are rotatively journaled in bearings 47 and 48 which are mounted on a raised front 49, of said platform 40, and said discs roll on the upper face of ring 37 and retain the outer 30 end of hand 3 in the relation shown in Fig. 3, to said ring. Companion lower retaining discs 35 50, only one being shown, engage the lower face of said ring 37 and retain the outer end of hand 3 against being elevated from the Fig. 3 position, with respect to said ring 37. Said disc 50 is mounted on spindle 51 that is rotatively journaled in bearing 52, mounted on the lower face of said platform section 49.

40 A propulsive means is shown for engaging ring 37, to advance the hand 3, and I preferably provide a pinion 53 which meshes with rack teeth 38. Said pinion 53 is supportingly journaled in a bearing 54, mounted on a bracket 55, that is anchored to section 49 of said platform. A shaft 45 55 is connected with pinion 53, by any suitable friction clutch 56, of well known type, that will under normal stress rotate said pinion 53 but which will slip and permit rotation of said shaft 55 and permit pinion 53 to remain stationary 50 upon abnormal stress, as will later appear. Shaft 55 is journaled in a bearing 57, and carries a bevel gear 58, that meshes with a bevel gear 59, journaled in a bearing 60, mounted on top of hand 3. A flexible shaft 61 transmits power 55 lengthwise of said hand 3.

Reference will next be made to the mechanism for locking the minute hand during periods intervening its advancing travel.

60 A lock block 62 is mounted on an arm 63 that is pivoted at 64 to hand 3. A spring 64, having one end connected to hand 3 and the other end connected with arm 63, normally urges block 62 toward the inner periphery of ring 37 and if desired, said block 62 may ride against said ring 65 between notches 39 so as to be ready to enter one of them when they are in registry with block 62, as the latter advances, it being understood that advancing movement of hand 3 is relatively slow. Arm 63 is connected by a link 70 65, with releasing arm 66, which is pivoted at 67, to hand 3. A releasing wheel 68, which is a gear of a train, is journaled at 69, on platform 40 and has a releasing stud 70 which is adapted to engage the lower free end of arm 66 and shift 75 it to the right of Fig. 3, owing to the clockwise

direction of rotation of wheel 68, and hence the block 62 will be withdrawn from a notch 39, and after stud 70 has released arm 66, by passing thereunder, spring 64 will return block 62 toward ring 37. Wheel 68 meshes with a pinion 71 fixed on gear 72 which are journaled at 73, on platform 40. Wheel 72, meshes with pinion 74 that is mounted on the shaft of a releasing motor 75, mounted on a bracket 76, on platform 40. The releasing motor 75 is electrically energized to cause the releasing operation to be performed, in a manner that will later be described in connection with the diagrammatic view shown in Fig. 6.

10 Reference will next be made to the means for driving gear 53 to advance hand 3, and I will refer to Figs. 1, 4, 5 and 7.

15 On the shelf 27 is mounted a propulsive electric motor 76 having a pulley that is suitably belted, as at 77, to the pulley 78, of a clutch shown in Fig. 7, the shaft 79 of which is journaled in bearings 80 and 81, which are mounted on shelf 27. Pulley 78 is one member of a friction clutch and the other member is indicated at 82 and has a sleeve 83 that is slidable and rotatable on a sleeve 84 of 100 pulley 78. On sleeve 84, is a small pulley 85 which may be belted at 86 to a larger pulley 87, journaled in bearings 88, which are mounted on shelf 27. Sleeve 84 has pairs of lugs 89 in which the elbows of bell crank governor arms 90, are 105 pivoted, as indicated at 91. The outer ends of said arms have weights 92 and the inner ends 93 bear against the outer end of sleeve 83 so that when the arms 90 spread by centrifugal action on rotation of pulley 78, the ends 93 will force clutch 110 member 82 into engagement with pulley 78 so that power transmission will be imparted to pulleys 85 and 87, and when the arms 90 are not under centrifugal force, the engagement of member 82 with member 78 will be released. Springs 115 may be provided, if desired, to normally urge arms 90 into a contracted position but this would be mere mechanical skill in view of this disclosure.

120 The flexible shaft 61, extends from gear 59, lengthwise of hand 3, down the hollow arbor 5, and emerges from the opposite end and then extends back to pulley 87, to which it is connected in driven relation. It will now be clear that I have provided a reducing train from propulsive motor 76, to pulley 87, and the manner 125 in which propulsive drive is transmitted from the axis of rotation of hand 3, to the outer end thereof will now be clear.

130 A bearing ring, fixedly mounted, is indicated at 94, Figs. 1 and 4, and the outer end of the hour hand is provided with a bracket 95, in which retaining discs 96 and 97 are rotatively mounted, and said discs engage opposite faces of said ring to retain the outer end of the hour hand in a given plane of rotation.

Reference will next be made to the diagrammatic view in Fig. 6.

135 A master clock, which may be of any suitable type, is indicated at 98 and will be usually disposed at a distance from the time indicator and in a place where it can be observed to insure correct time. The master clock has minute and hour hands 99 and 100, respectively. A contact disc adapted to be rotated with the second hand, is indicated at 101 and has a circuit closing segment 102 that is adapted to make contact with a contact bar 103, at each revolution of said disc 101 and close a circuit. I have shown a conductor 104, connected with bar 103 and with brush 35, and a conductor 105, connected with 140

disc 101 and with brush 36. A source of current is indicated at 106 and one side is connected by wire 107 with brush 34, and the other side or pole is connected by wire 108 with brush 33.

It will be understood that the wiring about to be described will extend through arbor 5, and the latter is shown in Fig. 6, to make the diagram clear. In practice, the wiring would extend along hand 3, but it is not thought necessary to show this in addition to the showing made in Fig. 6. Further, the wires extending internally of arbor 5, and which are electrically connected with contact rings 29 to 32, will in practice have brush contact therewith, as will be understood by those skilled in the electrical art, but this need not be shown in addition to the diagram about to be described.

Lead 109 extends from ring 29 to one pole 110 of propulsive motor 76. From the other pole 111, a lead 112 is electrically connected with arm 63 at bracket 64. A lead 113 connects with ring 30, and with a terminal 114, through which arm 63 is adapted to close circuit, as shown. A lead 115, is connected with lead 109, in advance of motor 76, at 116 and also with bracket 67, of arm 66.

A conductor 117, is connected at 118 with lead 113 and with pole 119 of releasing motor 75. The remaining pole 120, of said motor is connected with conductor 121 which is connected at its remaining end with ring 32. A lead 122 is connected with ring 31, at one end and at its remaining end is connected at 123 with wire 109 in advance of propulsive motor 76. The wheel 68 of the releasing train is connected by a wire 124 which is connected with wire 121 from pole 120, of releasing motor 75. It will be understood that the source of current 106 is at all times in full brush connection with rings 29 and 30.

The operation of the device will now be described in detail.

Assuming that hand 3 is locked with block 62 in engagement with a notch 39 of ring 37, as shown in Fig. 3, and that the master clock 98 is as shown in Fig. 6, the segment 102 will rotate clockwise, each revolution being a minute, until it engages terminal bar 103. Then the circuit will be closed and current will flow through wires 104 and 105 through brushes 35 and 36, respectively, to rings 31 and 32, respectively. Current will then flow from ring 31 through wire 122 to wire 109 and through wire 115 to bracket 67 of arm 66, as stud 70 is not yet in a position to engage arm 66 and close circuit therethrough.

The path of current from ring 32 will be through wire 121 to pole 120 and through motor 75 and pole 119 to wire 117 which connects with wire 113, the latter being connected with ring 30. Now the duration of contact of 102 and 103, at the master clock, is relatively short or limited but always sufficient to energize releasing motor 75 and cause it to run long enough to bring stud 70 into contact with arm 66. When this is accomplished, then circuit will be closed and current will pass from wire 124 back to pole 120 of motor 75 after segment 102 has passed out of circuit closing contact with terminal 103. Thus, after the circuit has been closed by stud 70 engaging arm 66, motor 75 will operate the releasing train long enough to withdraw block 62 from notch 39 as it will be understood that stud 70 will have to engage arm 66 until it retracts the latter to the right of Fig. 6, and passes free from the lower free end of said arm, after which the circuit is opened and the releasing motor will of course cease to run.

I will now describe the path of the current when stud 70 closes circuit through wheel 68. This path will be through ring 31 and wire 122 to wire 109 and through wire 115 to bracket 67, and through arm 66 to stud 70, wheel 68, wire 124 to pole 120 of motor 75. From pole 119 of motor 75 current will flow to wire 117 and back to ring 30, through wire 113, the circuit being completed through wire 109 which connects with ring 29.

It will now be clear that before the releasing train has released or withdrawn block 62 from notch 39, arm 63 will have been out of engagement with terminal 114, hence, the propulsive motor 76 would not start running to advance hand 3. However, in timed relation, the withdrawal of block 62, by shifting of arm 66 to the right of Fig. 6, would also shift arm 63 to the right and thereby engage it with terminal 114.

It will be understood that a suitable time is allowed for contact of stud 70 with arm 66 after block 62 has been withdrawn, to maintain engagement of arm 63 with terminal 114 long enough to cause motor 76 to run for such a duration as to move hand 3 from one notch 39 to another, and for this purpose, terminal 114 may be of a yielding nature and block 62 will be moved further than would be necessary for actual withdrawal from notch 39 as engagement of stud 70 with arm 66 will continue to cause motor 75 to run. However, the timed relation can better be controlled by providing arm 66 with a lower insulated portion 66' so that after block 62 has been withdrawn from notch 39 the circuit will be opened as soon as stud 70, passes off the conducting portion and onto the insulating portion 66', thereby arresting motor 75, but serving to hold arm 63 in engagement with terminal 114, to sufficiently advance hand 3.

I will now trace the path of current when the circuit is closed by arm 63 engaging terminal 114. The flow will be from ring 30 through wire 113 to terminal 114 and back through arm 63 to wire 112 and to pole 111 of propulsive motor 76, and through pole 110 thereof to wire 109 and back to ring 29.

Just as soon as a notch 39 has been reached, the stud 70 will have released arm 66 and spring 64 will return the arms 63 and 66 to the position shown in Fig. 3 and the block 62 will enter another notch to which the hand 3 has been advanced.

However, I prefer to only withdraw the block 62 from a notch merely far enough to release hand 3 and let the outer edge of block 62 ride on the inner periphery of ring 37 until it reaches the next notch so that the spring 64 can the more readily shift block 62 into such notch. This is the reason why the friction slip clutch 56 is employed so that when even the slowly moving hand 3 is halted, the drive will not be disrupted.

Further, it is important to give the propulsive motor a chance to gain speed before a full load is imposed and it will be clear that before motor 76 starts, the governor arms 90 (Fig. 7) will be in a contracted position and clutch member 82 will be loosely engaged with member 78 and this will allow the propulsive motor freedom to start. However, just as soon as motor 76 gets started, the governor arms 90 will spread and force clutch member 82 into engagement with member 78 and this will transmit drive to gear 53. This clutch has another function in that when the block 62 is shifted into a notch the hand 3 is suddenly arrested at which time the propulsive motor 76 is cut out of circuit. However, momentum of the

revolving parts would cause a slight further rotation of motor 76 and its reducing train at a suddenly slower speed and hence the governor arms would contract and release the clutch member 82 from member 78 so that the motor 76 could gradually cease rotation.

It will be seen that if the clutch 56 is used, in addition to the clutch shown in Fig. 7, that a double precaution is provided against suddenly 10 stopping motor 76, and hence, in some embodiments, the clutch 56 can be dispensed with, more especially when the driving means engaging the ring 37 is tractive instead of the positive type herein shown. Further, it will be noted that I 15 will preferably rely upon automatic engagement of block 62 with the notches 39, with the block riding on the inner periphery of ring 37, between the notches and therefore engagement of said block 62 with the notches will be the controlling factor. In view of slippage of the 20 clutches, which is desirable, I will arrange such excess of movement of the releasing train over what would be essential in the absence of said clutches so as to at all times insure sufficient advancing movement of hand 3 to make sure that the block 62 will reach the next notch.

It will now be clear that motor 75, which causes withdrawal of block 62, functions in this particular embodiment, in slightly overlapping relation 30 to motor 76, which causes advancing movement of the minute hand 3, but in substance, and in actual functioning, the said motors operate alternately with respect to each other.

While the counter-weight with which hand 3 is 35 provided, greatly reduces the stress on the propulsive mechanism and is highly advantageous for that reason, still, it is not in all respects absolutely essential, more especially where the means for advancing hand 3, is the positive type 40 herein shown.

The feature whereby the minute hand 3, and 45 thereby the hour hand 4, are both locked and positively held in the position to which they have been advanced and throughout the period between their advance, is highly important in cases where these hands are of gigantic proportions since it enables the hands to correctly indicate the time of day or night irrespective of any slack that might develop, this being especially true of 50 the minute hand 3, and also of the hour hand where the dial train has no slack.

As the power to advance the minute hand is applied at the outer end thereof, or in other words at the free end thereof, said hand is not put to 55 any abnormal stress such as would be true if it were revolved by means applied near the center of rotation.

It is believed that the invention will be fully 60 understood from the foregoing description, and while I have herein shown and described one specific form of this invention, I do not wish to be limited thereto except for such limitations as the claims may import.

I claim:—

65 1. A distance time indicator comprising, a clock dial, a hollow rotatable arbor, minute and hour hands rotatable about the axis of said arbor, a dial train controlling relative movement of said hands,

a driving electric motor carried by said arbor, a releasing electric motor carried by said minute hand, a locking ring near said dial having rack teeth and locking notches, a propulsive gear meshing with said rack teeth and operated by said driving motor for advancing said minute hand intermittently, a locking block normally urged to engage said notches to lock said minute hand between intermittent advancement of the latter, a source of current, a master clock having a circuit closer, and an electric circuit including said master clock and source of current and said driving and releasing motors for causing alternate operation of the latter to advance and release said minute hand. 80

2. A distance time indicator comprising, a clock dial, a rotatable arbor, a minute hand fixed on said arbor, a dial train partly mounted on said arbor and driven thereby, an hour hand driven by said dial train, a rack and holding ring near said dial, a propulsive motor carried by said arbor and having means carried by said minute hand and engaging said ring to advance said minute hand and arbor and through said dial train advance said hour hand, and a releasing 95 motor carried by said minute hand and having means coacting with said ring to lock and release said minute hand. 95

3. A distance time indicator comprising, a clock dial, a rotatable arbor, a minute hand fixed on said arbor, a dial train driven by said arbor, an hour hand driven by said dial train, a propulsive and locking ring near said dial, a propulsive motor operatively connected with said minute hand and ring to advance said minute 105 hand and arbor and through said dial train advance said hour hand, and a releasing motor operatively connected with said minute hand and ring for releasing said minute hand for advance movement. 115

4. A distance time indicator comprising, a clock dial, a rotatable arbor, a minute hand fixed on said arbor, a dial train driven by said arbor, an hour hand driven by said dial train, a propulsive and locking ring near said dial, a propulsive motor operatively connected with said minute hand and ring to advance said minute 120 hand and arbor and through said dial train advance said hour hand, locking means normally acting to lock said minute hand in its advanced position, a releasing motor actuating said locking means for releasing said minute hand to permit advance thereof, and mechanism for causing timed alternate action of said propulsive and releasing motors. 125

5. In a distance time indicator, a clock dial, minute and hour hands movable abreast of said dial, an electric circuit including a source of current, an electric propulsive motor in said circuit for advancing said hands, a releasing electric motor in said circuit for releasing said hands to permit the latter to be advanced, a master clock in said circuit for timed closing and opening of said circuit, and means in said circuit for causing alternate operation of said releasing and propulsive motors to release and advance said hands when said circuit is closed. 135

LEONARD C. BUTTS.
